TOY BLENDER

Meyer Saffer, 89-11 153rd St., Jamaica, N.Y.

Filed Jan. 20, 1960, Ser. No. 59,120

Term of patent 14 years

(Cl. D34—15)

I claim:

The ornamental design for a toy blender, substantially as shown.
